attorney.

UNITED STATES PATENT OFFICE.

PAUL G. WIEGERT, OF CHICAGO, ILLINOIS, ASSIGNOR OF ONE-HALF TO THE STANDARD COMPANY, OF CHICAGO, ILLINOIS, A CORPORATION OF OHIO.

SASH-WEIGHT.

No. 911,352.

Specification of Letters Patent.

Patented Feb. 2, 1909.

Application filed February 12, 1908. Serial No. 415,514.

To all whom it may concern:

Be it known that I, PAUL G. WIEGERT, a resident of Chicago, in the county of Cook and State of Illinois, have invented a new 5 and useful Improvement in Sash-Weights; and I do hereby declare the following to be a full, clear, and exact description thereof.

My invention relates to sash-weights and has special reference to such weights that are 10 formed from cast metal, such as iron.

The object of my invention is to provide a cheap, simple and efficient form of a sash-weight which can be easily and quickly formed for use with a guiding rod in a window frame, as well as one which can be easily, 15 properly and always guided true within a narrow and hollow frame.

My invention consists, generally stated, in the novel arrangement, construction and 20 combination of parts, as hereinafter more specifically set forth and described and particularly pointed out in the claim.

To enable others skilled in the art to which my invention appertains to construct and use 25 my improved sash weight, I will describe the same more fully, referring to the accompanying drawing, in which:—

Figure 1 is a vertical section of a window frame jamb showing my improved sash-weight applied thereto. Fig. 2 is a side elevation of the sash-weight with the ends of the same shown in section. Fig. 3 is an enlarged top view of the weight. Fig. 4 is an enlarged cross-section of the same on the 35 line 4—4 Fig. 2.

Like symbols of reference herein indicate like parts in each of the figures of the drawing.

As illustrated in the drawing, 1 represents 40 my improved sash-weight, which is of the usual shape and size, and is formed of cast metal, such as iron. Before the casting of the weight 1 a short section of a metal tube or pipe 2 formed of steel or brass is placed 45 within the mold cavity for forming said weight and during the casting of the same the body of the weight is cast around said pipe. The pipe 2 will thus act as a cover during such molding or casting of the weight 50 1 and it preferably extends slightly beyond the upper end 1' of the said weight, as at 2', so that such pipe when formed within said weight will act as a lining for the same and form a bearing by its interior surface 3 for

the guiding rod 4 to be employed therewith, 55 as hereinafter described.

When my improved sash-weight 1 is so formed and it is desired to use the same within a window jamb 5, the following construction is preferably employed therewith. The 60 guiding rod 4 is generally located centrally of the hollow portion 6 of the jamb 5 and is supported at its lower end in a bracket 7 extending into said hollow portion from the inner face of said jamb. The lower end of the rod 4 is threaded and extends through the bracket 7, so that a nut 8 can engage with said end and hold the same in place at this point. The upper end of the rod 4 is extended or 65 bent inwardly toward the inner face of the 70 jamb 5, as at 9, and is secured thereto by the screws 9'.

The weight 1 is placed around the rod 4 and is adapted to travel vertically along the same by being guided on said rod through 75 the bearing surface 3 in the pipe 2 within the same fitting around the rod. Between the lower end of the weight 1 and the bracket 7 and fitting around the rod 4 by an opening through the same is a bumper 10, which is 80 formed of any suitable flexible material, preferably rubber, and such bumper is supported by said bracket so that it can engage with the lower end of the said weight when 85 it is lowered or dropped upon the same.

The guiding and bearing lining or pipe 2 in the weight 1 is shown as applied centrally of said weight and at one side of the weight and adjacent to said pipe is an eye 11, which is secured in the upper end 1' of said weight 90 in any suitable manner, so that one end of the chain 12 can be connected to the same and be passed over the pulley 13 mounted in the bracket 14 on the inner face of the jamb 5, for being connected at its opposite end in any 95 suitable manner to the sash (not shown). It will thus be seen that my improved sash-weight can be operated with very little friction on the parts and will enable a permanently fixed guiding rod to be employed with 100 the same, while the weight can be operated easily and noiselessly and will not be liable to get out of alignment or come in contact with the frame or other parts.

It will be obvious that the lining or bearing 105 for the weight may be located at other positions in the same and the parts composing the said weight may be formed of any suit-

able materials, while various other changes and modifications in the design, shape and construction of the weight may be resorted to without departing from the spirit of the invention, or sacrificing any of its advantages.

What I claim as my invention, and desire to secure by Letters Patent, is:—

As a new article of manufacture, a sash

weight provided with a tube or pipe within 10 the same for forming a bearing therein and having the weight cast around the same.

In testimony whereof, I the said PAUL G. WIEGERT, have hereunto set my hand.

PAUL G. WIEGERT.
